DESIGN FOR A DISPLAY CONTAINER FOR GOLF BALLS AND TEES

Richard K. Hines, New York, N. Y.

Application November 17, 1938, Serial No. 81,184

Term of patent 14 years

To all whom it may concern:

Be it known that I, Richard K. Hines, a citizen of the United States, residing at New York, State of New York, have invented a new, original, and ornamental Design for a Display Container for Golf Balls and Tees, of which the following is a specification, reference being had to the accompanying drawing, forming part thereof.

Figure 1 is a perspective view of a display container for golf balls and tees, showing my new design; and

I claim:

The ornamental design for a display container for golf balls and tees, substantially as shown.

RICHARD K. HINES.
